CYLINDER HONE

Edward D. Wilkerson, Orange, N. J.

Application March 25, 1946, Serial No. 656,960

6 Claims. (Cl. 51—184.2)

1

The invention relates generally to hone structures and primarily seeks to provide a novel cylinder hone which is simple in construction and can be manufactured at low cost, and in which the cylinder wall engaging stones are mounted in a novel manner enabling them to readily conform to and efficiently hone cylinder surfaces which are not entirely true and uniform.

Cylinder honing devices are known in which there are included a shaft insertable axially into a cylinder, and cylinder wall honing elements carried by the shaft and effective as the shaft is rotated to engage and hone the cylinder walls. In some of these known devices the honing elements are swingably mounted at longitudinally spaced points on a rigid carrying shaft, and in such devices it is impossible for the honing elements to conform to cylinder wall surfaces engaged thereby and which are not true and uniform. This is due to the fact that the rigid shaft mounting causes the swinging honing elements always to remain in parallel relation to the axis of the rigid shaft. Therefore, it is an object of the present invention to provide a novel cylinder honing device in which the honing head including the honing elements and the swingable mountings therefor is so constructed as to be capable of flexing in two planes, one along and one across the axis of the head, thereby to permit the honing elements to properly engage in honing contact with cylinder walls that are not true and uniform.

An object of the invention is to provide a honing device of the character stated, including a shaft insertable axially into a cylinder to be honed and having longitudinally spaced thereon two support members, and a plurality of honing elements swingably mounted on the support members and adapted to engage and hone cylinder wall surfaces as the shaft is rotated, said shaft having a flexible section between the longitudinally spaced support members capable of flexing about and along its axis in a manner for enabling the honing elements to conform to cylinder wall surfaces that are not true and uniform.

With the above and other objects in view that will hereinafter appear, the nature of the invention will be more clearly understood by reference to the following detailed description, the appended claims, and the several views illustrated in the accompanying drawings.

In the drawings:

Figure 1 is a side elevation illustrating a hone structure embodying the invention, parts being broken away and in section.

Figure 2 is a vertical cross section taken on the line 2—2 on Figure 1.

Figure 3 is a somewhat diagrammatic vertical sectional view illustrating the improved hone structure in the process of honing a cylinder

2

wall which is slightly tapered the arm engaging springs and the spring covering cap being omitted for purposes of clarity.

Figure 4 is a view similar to Figure 3 illustrating the manner in which rigidly mounted honing elements engage a slightly tapered cylinder wall.

In the example of embodiment of the invention herein disclosed, the improved hone structure includes a flexible shaft 5 having a head 6 brazed or otherwise secured on one end extremity thereof, and a driver head 7 brazed or otherwise secured on the other end extremity thereof.

The head 6 has an end face 8 forming part of a sphere, and its upper face 9 is disposed perpendicular of the axis of the shaft. Three pins 10 project from the face 9 in equidistantly spaced relation and with their axes paralleling the axis of the shaft 5.

Spaced a distance above the head face 9 is a disk 11, said disk being brazed or otherwise secured to the shaft 5. If desired, the edges of the disk may be cut away or notched in the manner clearly illustrated in Figure 2, and three pins 12 project from said disk toward the driving head 7, or in other words in the same direction of projection as the pins 10 and in axial alignment with said pins.

Three U-shaped stone carriers generally designated 13 are provided and each thereof comprises a U-base 14 and two arms 15, the latter being disposed perpendicular to the axis of the shaft 5, and the base 14 being disposed in parallel relation to the axis of said shaft. Each carrier member base 14 includes a channel or groove 16 extending throughout the major portion of its length between the arms 15, and in each channel is secured a honing stone 17. It will be apparent by reference to Figure 2 of the drawings that the outwardly projected portion of each honing stone is convexly curved as at 18 and projects slightly beyond the edge portions of the channel in which it is mounted.

Each carrier arm 15 is provided with an aperture 19 to fulcrum on one of the pins 10 or 12, and inwardly of each said aperture, each arm disposed to overlie the plate 11 is equipped with a headed stud 20. A retractile spring 21 is connected at its ends to each adjacent pair of the arm studs 20, and it will be apparent by reference to Figure 2 that the springs constantly tend to force the stones 17 outwardly.

A cap 22 is slidable along the shaft 5 and is recessed as at 23 at the end thereof disposed toward the plate 11 so as to house and protect the springs 21. The cap is normally secured by a set screw 24 in position for housing the springs 21 and for closely overlying the adjacent carrier arms 15 in a manner for retaining the carriers on the fulcrum pins 10 and 12 without interfering with the free swinging of the carriers about said pins.

In the use of the improved honing device, the operator grips the honing elements so as to contract them against the action of the springs 21 and inserts the honing head axially into the cylinder to be honed. The driving head 7 is chucked in a suitable driving device (not shown) and rotation is imparted to the head to cause the same to rotate in the cylinder with the honing stones 17 rapidly dragging over the surface to be honed. It will be obvious that the action of the springs 10 21 and also centrifugal force will hold the honing stones against the cylinder wall.

Should the device be employed in the honing of a cylinder wall surface not entirely true and uniform, the flexible section of the shaft extending between the head 6 and the plate 11 is free to flex about, and also along its axis in order to permit the honing stones to accurately conform to and properly engage the cylinder wall. In this instance, the springs 21 urge the stones against the smallest diameter 25 of the cylinder 26, and then by the combined action of the springs and centrifugal force the shaft 5 flexes and twists slightly between the head 6 and the plate 11, and in so doing permits the head 6 and the plate 11 to move relatively and allow the carriers to properly align the stones against the cylinder wall surfaces being honed.

It will be apparent by reference to Figure 4 that should a honing head having a rigid shaft section 29 be employed in the honing of a slightly tapered cylinder wall, the stones 30 would contact the cylinder wall properly only at the small diameter end and would be slightly spaced from the wall at the other end as at 31.

While one form of the invention has been shown for purposes of illustration, it is to be clearly understood that various changes in the details of construction and arrangement of parts may be made without departing from the spirit and scope of the invention as defined in the appended claims.

I claim:

1. A cylinder honing device including a shaft insertable axially into a cylinder to be honed and having longitudinally spaced thereon two support members, and a plurality of honing elements supported for outward and inward movement on said support members and adapted to engage and hone cylinder wall surfaces as the shaft is rotated, said shaft having a flexible section between the longitudinally spaced support members capable of flexing about and along its axis in a manner for enabling the honing elements to conform to cylinder wall surfaces that are not true and uniform.

2. A cylinder honing device including a shaft insertable axially into a cylinder to be honed and having longitudinally spaced thereon two support members, and a plurality of honing elements supported for outward and inward movement on said support members and adapted to engage and hone cylinder wall surfaces as the shaft is rotated, said shaft being flexible from end to end including that portion between the longitudinally spaced support members capable of flexing about and along its axis between said support members in a manner for enabling the honing elements to conform to cylinder wall surfaces that are not true and uniform.

3. A cylinder honing device including a shaft insertable axially into a cylinder to be honed and having longitudinally spaced thereon two support members, a plurality of honing elements swing-

ably mounted on said support members and adapted to engage and hone cylinder wall surfaces as the shaft is rotated, said elements including U-shaped carriers having arms fulcrumed on pins projecting in like direction from both support members and paralleling the axis of the shaft, and a cap slideable along said shaft and removably secured thereon in position for retaining the carrier arms on said pins.

4. A honing device as defined in claim 1 in which the honing elements include U-shaped carriers having arms fulcrumed on pins projecting in like direction from both support members and paralleling the axis of the shaft, and in which there is included a cap slideable along the shaft and removably secured thereon in position for retaining the carrier arms on the pins.

5. A cylinder honing device including a shaft insertable axially into a cylinder to be honed and having longitudinally spaced thereon two support members, a plurality of honing elements swingably mounted on said support members and adapted to engage and hone cylinder wall surfaces as the shaft is rotated, said elements including U-shaped carriers having arms fulcrumed on pins projecting in like direction from both support members and paralleling the axis of the shaft, the arm at one end of each said carrier arm also having a stud projecting therefrom inwardly of its fulcrum, retractile springs connected to adjacent pairs of studs and constantly tending to force the honing elements outwardly, and a cap slideable along said shaft and removably secured thereon in position for retaining the carrier arms on said pins and having a recess therein disposed to house the springs.

6. A cylinder honing device including a shaft insertable axially into a cylinder to be honed and having longitudinally spaced thereon two support members, a plurality of honing elements swingably mounted on said support members and adapted to engage and hone cylinder wall surfaces as the shaft is rotated, said elements including U-shaped carriers having arms fulcrumed on pins projecting in like direction from both support members and paralleling the axis of the shaft, the arm at one end of each said carrier arm also having a stud projecting therefrom inwardly of its fulcrum, retractile springs connected to adjacent pairs of studs and constantly tending to force the honing elements outwardly, and a cap slideable along said shaft and removably secured thereon in position for retaining the carrier arms on said pins and having a recess therein disposed to house the springs, said shaft having a flexible section between the longitudinally spaced support members capable of flexing about and along its axis in a manner for enabling the honing elements to conform to cylinder wall surfaces that are not true and uniform.
